UNITED STATES PATENT OFFICE.

HERMAN KRAUTH, OF MERIDEN, CONNECTICUT, ASSIGNOR TO CLARENCE W. FOX, OF SANGUS, MASSACHUSETTS.

DESIGN FOR A WALL-BRACKET.

SPECIFICATION forming part of Design No. 27,728, dated October 12, 1897.

Application filed August 19, 1897. Serial No. 648,836. Term of patent 7 years.

To all whom it may concern:

Be it known that I, HERMAN KRAUTH, of the town of Meriden, New Haven county, Connecticut, have invented and produced a new and original Design for Wall-Brackets, of which the following is a specification, reference being had to the accompanying drawing, forming a part thereof.

The drawing shows a side view of my newly-
designed wall-bracket.

As shown in the drawing, the leading or material feature of my design consists of a pair of curved border-pieces, separated next to the wall-plate and gradually converging toward the extremity of the bracket, and open scrollwork and ornamentation filled in between said border-pieces.

The wall-plate *a*, ornamented at top and bottom, has a projecting arm, and the latter

has curved border-pieces *b b*, separated a considerable distance next to the wall-plate, said pieces gradually approaching each other toward the extremity of the arm, and the space between said border-pieces *b b* is filled with open scrollwork *c* and ornamental pieces *d*. The border-pieces *b b* have projecting ornaments *e*.

I claim—

The design for a wall-bracket herein shown and described.

In testimony whereof I have signed my name to this specification in the presence of two subscribing witnesses.

HERMAN KRAUTH.
